METHOD AND MACHINE FOR MAKING SANITARY NAPKINS

August P. Jurgensen, Atlantic City, N. J., assignor to The De Long Hook and Eye Company, a corporation of Pennsylvania

Application June 17, 1933, Serial No. 676,342

10 Claims. (Cl. 223—15)

This invention relates to the art of making sanitary napkins, and involves improvements in the method and means for making sanitary napkins and similar articles wherein pads of absorbent material are severed from a strip of absorbent material which is preferably fed intermittently to the severing means, and the severed pads are transferred to and deposited at intervals upon a strip of gauze which is subsequently folded about the spaced pads and severed between adjacent pads.

One of the principal objects of the invention is the simplification of both the method and the mechanism for making sanitary pads in this manner. Another object of the invention is the provision of an improved method and improved means whereby the operation of severing the pads from the strip of absorbent material is utilized to transfer the severed pads into a position such that they may be deposited upon the strip of gauze by the next subsequent operation of the severing and transferring means. A further object of the invention is the provision of an improved method and improved means whereby the operation of severing the pads from the strip of absorbent material delivers the severed pads to a position of rest above the strip of gauze whereby the pad in the position of rest is released upon the next subsequent operation of the pad severing and transferring means, thereby insuring the proper spacing of the pads upon the gauze and producing a uniform product. It is a still further object of the invention to provide improved means for stripping the previously severed pad from the severing and transferring means.

Other objects and advantages of the improvements will be apparent from the following description, taken with the accompanying drawings wherein:

Fig. 1 is a plan view, partly in section, showing a preferred form of means for severing absorbent pads from an intermittently advanced strip of absorbent material and delivering the same to a continuously fed strip of gauze;

Fig. 2 is an enlarged, vertical sectional view taken longitudinally of the strip of gauze, on the line 2—2 of Fig. 1;

Fig. 3 is an enlarged, vertical sectional view taken longitudinally of the strip of absorbent material, on the line 3—3 of Fig. 1;

Fig. 4 is a still further enlarged, vertical sectional view similar to Fig. 3, but showing the pad severing and transferring means in its lowermost position;

Fig. 5 is a sectional view similar to Fig. 4, showing the operation of the stripping means;

Fig. 6 is a horizontal sectional view of a portion of the machine in Fig. 1, showing the manner in which an elongated pad is severed from the forward end of the strip of absorbent material; and

Fig. 7 is a perspective view of a sanitary napkin made by the improved method and the improved means disclosed herein.

The novel method herein described is preferably carried out by means of mechanism supported upon a frame 10. A bed plate 11 is supported upon the frame 10 and forms a table for the strip of gauze 12 in its movement through the machine. The bed plate 11 carries a pair of oppositely arranged guide members 13 spaced from each other to provide a channel or trough 14 for the strip of gauze 12. The strip of gauze is preferably fed through the channel 14 by means of a continuously driven feed belt 15 the upper run of which is carried by the bed plate 11 and has its edges engaged within undercut channels 16 in the inner edges of the guide members 13. One end of the feed belt passes about a roller 17 carried by a shaft 18, and the belt is continuously driven by any suitable mechanism, the disclosure of which is unnecessary herein.

Superposed upon the bed plate 11 is a second bed plate 19 over which the forward end of a strip of absorbent material 20 is advanced, preferably by means of a pair of feed belts 21, 22 as shown in Fig. 3. These feed belts are arranged to be moved intermittently in order to provide an intermittent feed for the strip of absorbent material 20. The particular mechanism by which this feed is secured is not material to the present improvements and is therefore not disclosed herein.

In the path of movement of the strip of absorbent material 20 an elongated opening 23 is provided in the upper bed plate 19 in vertical alignment with the gauze channel 14. A cutting die 24 is secured in the upper end of this opening and is provided with an opening 25 therethrough shaped to conform to the shape of the absorbent pads severed from the strip of absorbent material 20. A cooperating cutting punch 26 is secured by means of bolts 27 or otherwise to a supporting plate 28 carried upon the upper ends of two pairs of bars 29 mounted for sliding movement in suitable openings in the superposed bed plates 11 and 19 heretofore referred to. The lower ends of the bars 29 have mounted thereon a crosshead 30 from which a connecting rod 31

- 31 extends to a crankshaft or other suitable form of power transmitting mechanism not herein disclosed.
- In the form of the improvements herein disclosed, the strip of gauze 12 is preferably fed continuously by the feed belt 15 in the direction indicated by the arrows in Figs. 1 and 6, and the strip of absorbent material 20 is preferably fed intermittently in a direction transverse to the direction of movement of the strip of gauze. The intermittent feed for the strip of absorbent material 20 is so timed as to advance the strip at each forward movement thereof a distance equal to the width of the opening 25 in the cutting die 24. The length of the opening 25 in the cutting die is preferably equal to the width of the strip of absorbent material 20, this width ordinarily constituting the length of the absorbent pads severed from the strip. It will be apparent, therefore, that each intermittent movement of the strip of absorbent material advances the forward end of the strip a distance equal to the width of each pad and into a position overlying the opening in the cutting die. The parts 25 of the machine are so timed that during the interval when the strip of absorbent material is at rest the cutting punch 26 is moved downwardly by means of the connecting rod 31, thereby severing the forward end of the strip of absorbent material to provide an absorbent pad 32.
- As disclosed herein, the cutting punch 26 is provided with parallel side cutting edges 33 and parallel end cutting edges 34, with the corners thereof removed as clearly shown at 35 in Fig. 6, and the opening 25 in the cutting die is shaped to accord therewith. In the operation of the co-operating parts of the die cutting mechanism in severing a pad 32 from the forward end of the strip of absorbent material 20 severing action 40 takes place along only one of the parallel side edges of the pad, although, as will be clear from the showing in Fig. 6, the downward movement of the cutting punch 26 operates to sever the two triangular corners 36 at each operation of the die. These corners may remain upon the bed plate 19 to be pushed forwardly thereover by the subsequent movements of the strip 20, or they may be removed from the machine in any suitable manner, and the provision of means 45 for their removal forms no part of the present invention and is not disclosed herein.
- As shown in Figs. 2 and 3, the cutting punch 26 is in its raised position and the strip of absorbent material has been advanced so that the forward end thereof is in position over the opening 25 in the cutting die. When the cutting punch moves downwardly to sever the forward end of the strip of absorbent material to form an absorbent pad, it continues its movement beyond the severing position to thereby carry the severed pad 32 downwardly through the opening in the cutting die, as shown in Fig. 4. In order to prevent the severed pad from dropping freely through the opening 23 in the bed plate 19 onto the continuously moving strip of gauze, it is preferable to provide some means for bringing the previously severed pad to a position of rest so as to insure that the pads will be deposited at proper intervals upon the continuously moving strip of gauze. 50 For the purpose of accomplishing this, a pair of flat springs 37 is provided in the opposite side walls of the opening 23 through the bed plate, below the cutting die. The lower ends of the springs 37 are supported upon shoulders 38 formed in the side walls of the opening through the bed

plate, and the upper ends are freely mounted for sliding movement in a cut-away portion 39 of the cutting die. The intermediate portions 40 of these springs are bowed inwardly slightly beyond the faces of the opening through the bed plate, and the cutting punch is arranged to move downwardly to a position to deliver the previously severed pad 32 to these retaining springs.

Upon the next subsequent downward movement of the cutting punch and the pad severed thereby, the pad retained in position between the springs 37 will be forced therefrom and thus be free to drop upon the moving strip of gauze. The provision of means for retaining the individually severed pads in a position of rest between the severing position and the moving strip of gauze insures that the pads will be delivered to the gauze at intervals timed in accordance with the downward movements of the cutting punch, and an accurate spacing of the pads upon the strip of gauze is thus obtained. Such a provision is particularly desirable on account of the tendency of some of the pads to adhere to the punch, while others drop freely therefrom upon being severed, thus producing an unequal spacing of the pads upon the strip of gauze. By this method, and by the means shown herein, it is apparent that there will be no noticeable variation in the ends 41 of the folded gauze which extend beyond the enfolded pad, as shown in Fig. 7.

In order to prevent a previously severed pad from adhering to the cutting punch 26, means is provided for stripping the pads from the lower face thereof following the severing operation. This means comprises a rod 42 slidably mounted in aligned openings through the supporting plate 28 and the cutting punch 26, and having an enlarged head 43 on the lower end thereof for engagement within a countersink 44 in the upper wall of the cutting punch. The stripper device 40 and the cutting punch are so designed and so timed in their operation that the stripper preferably moves downwardly with the cutting punch, and when the cutting punch begins its upward movement the stripper head has moved into a position 45 in contact with the upper surface of the previously severed pad. This operation insures the separation of the pad from the punch, and upon the upward withdrawal of the stripper head the pad remains in a position of rest between the oppositely arranged retaining springs 37. Upon the next subsequent downward movement of the pad severing and transferring device, the pad in position of rest between the springs 37 is pushed therefrom by engagement therewith of the pad carried downwardly by the cutting punch, and as the latter pad is carried into position between the retaining springs, the pad previously held by the springs drops freely upon the strip of gauze.

Inasmuch as the strip of gauze is fed continuously beneath the cutting die, the strip with the pads spaced thereon at intervals is moved forwardly between a suitable folding device 45, as shown in Figs. 1 and 6, whereby the edges of the gauze are folded into overlapping relation over the pads, and the folded strip is subsequently severed between adjacent pads by a suitable cutting device to produce sanitary napkins in the form shown in Fig. 7. As will be understood, the protruding ends of gauze 41 may then be folded into 70 overlapping relation over the encased pads, whereupon the napkins may be packaged in such manner as may be desired.

While a method has been disclosed herein, together with novel apparatus for carrying out the 75

same, whereby a strip of gauze is fed continuously in one direction and absorbent pads are severed from a strip of absorbent material fed intermittently in a direction at right angles thereto, the invention is not intended to be limited in this manner. By the improvements herein disclosed, the absorbent pads are severed from a strip of absorbent material in a position in vertical alinement with the strip of gauze, and, by the same 10 operation of the severing device, the pads are transferred to a position from which they are free to drop upon the strip of gauze. It is not altogether essential, therefore, that the strip of absorbent material be advanced in a direction transverse to the strip of gauze. The invention may be practiced with other directions of movement of the strips of absorbent material and gauze with respect to each other, although it is essential that the pads be deposited on the gauze lengthwise thereof. If the pads are severed from an absorbent strip moving in a direction other than at right angles to the strip of gauze, suitable means may be provided for turning each severed pad as it moves downwardly from the severing position. This may readily be effected by rotating the cutting punch about a vertical axis during the downward movement of the punch following the severing operation.

Various other changes from the embodiment of 30 the inventions disclosed herein will suggest themselves to those skilled in the art to which the improvements relate, and such changes are contemplated as come within the scope of the appended claims.

Having thus described the invention, what I desire to claim by Letters Patent is:

1. In the art of making sanitary napkins, the method which comprises continuously feeding a strip of gauze in a given direction, intermittently feeding a strip of absorbent material above the strip of gauze and in a direction transverse to the direction of feed thereof, intermittently severing the forward end of the strip of absorbent material vertically above the strip of gauze to provide elongated absorbent pads, transferring the pads in a vertical direction to a position of rest above the strip of gauze, and depositing the pads at spaced intervals lengthwise of the strip of gauze.

2. In the art of making sanitary napkins, the method which comprises continuously feeding a strip of gauze in a given direction, intermittently feeding a strip of absorbent material above the strip of gauze and in a direction transverse to the direction of feed thereof, intermittently severing elongated absorbent pads from the strip of absorbent material in a position above the strip of gauze and, by the same operation, transferring the absorbent pads in a vertical direction to a position of rest above the strip of gauze, and depositing the pads lengthwise upon the strip of gauze.

3. The method of making sanitary napkins which comprises continuously feeding a strip of gauze in a given direction, intermittently feeding a strip of absorbent material above the strip of gauze and in a direction transverse to the direction of feed thereof, intermittently severing the forward end of the strip of absorbent material vertically above the strip of gauze to provide absorbent pads, transferring the pads vertically to a position of rest above the strip of gauze, depositing the pads at intervals upon the strip of gauze, folding the edges of the strip of gauze into overlapping relation about the absorbent pads

deposited thereon, and severing the folded gauze between the absorbent pads.

4. In the art of making sanitary napkins, the method which comprises continuously feeding a strip of gauze, intermittently feeding a strip of absorbent material above the strip of gauze, intermittently severing elongated absorbent pads from the strip of absorbent material in a position vertically above the strip of gauze, transferring the pads individually in a vertical direction into a position of rest lengthwise above the strip of gauze, and depositing the pads at intervals upon the strip of gauze.

5. In a machine for making sanitary napkins wherein a strip of absorbent material is intermittently fed in one direction and a strip of gauze is continuously fed beneath the strip of absorbent material, mechanism for severing absorbent pads from the strip of absorbent material and depositing the same at intervals lengthwise of the strip 20 of gauze comprising a stationary cutting die mounted beneath the forward end of the strip of absorbent material and having an opening therethrough in alinement with the strip of gauze, a reciprocatory cutting punch mounted above the 25 forward end of the strip of absorbent material for movement into and out of said cutting die to sever a pad from the strip of absorbent material and convey the same downwardly into said die, and stationary pad holding means for receiving 30 a severed pad delivered thereto upon a downward movement of the cutting punch and for delivering the same to said strip of gauze upon the subsequent downward movement of the cutting punch and the pad severed thereby.

6. In a machine for making sanitary napkins wherein a strip of absorbent material is intermittently fed in one direction and a strip of gauze is continuously fed in a direction transverse thereto beneath the strip of absorbent material, 40 mechanism for severing absorbent pads from the strip of absorbent material and depositing the same at intervals lengthwise of the strip of gauze comprising a stationary cutting die mounted between the strip of absorbent material and the strip of gauze and having an opening therethrough in alinement with the strip of gauze, a reciprocatory cutting punch mounted above the 45 strip of absorbent material for movement into and out of said cutting die to sever a pad from the strip of absorbent material and convey the same downwardly through said die, and resilient means for retaining a severed pad delivered thereto upon a downward movement of the cutting punch and for delivering the same to said 50 strip of gauze upon the subsequent downward movement of the cutting punch and the pad severed thereby.

7. In a machine for making sanitary napkins wherein a strip of absorbent material is intermittently fed in one direction and a strip of gauze is continuously fed in a direction transverse thereto beneath the strip of absorbent material, mechanism for severing absorbent pads from the strip of absorbent material and depositing the same at intervals lengthwise of the strip of gauze comprising a bed plate 60 for supporting the strip of absorbent material and having a pad delivering opening therein between the forward end of the strip of absorbent material and the strip of gauze, a cutting die mounted in said opening, a reciprocatory cutting punch mounted for movement into and out of said cutting die to sever a pad from the strip of absorbent material and convey the same downwardly 65 70 75

- through said die, and means for retaining a severed pad within said opening upon a downward movement of the cutting punch and for delivering the same to said strip of gauze upon the subsequent downward movement of the cutting punch and the pad severed thereby.
8. In a machine for making sanitary napkins wherein a strip of absorbent material is intermittently fed in one direction and a strip of gauze is continuously fed in a direction transverse thereto beneath the strip of absorbent material, mechanism for severing absorbent pads from the strip of absorbent material and depositing the same at intervals lengthwise of the strip of gauze comprising a stationary cutting die mounted between the strip of absorbent material and the strip of gauze, a reciprocatory cutting punch mounted above the strip of absorbent material for movement into and out of said cutting die to sever a pad from the strip of absorbent material and convey the same downwardly through said die in alinement over said strip of gauze, and means mounted on said cutting punch and relatively movable with respect thereto to strip the severed pads from said punch.
9. In a machine for making sanitary napkins wherein a strip of absorbent material is intermittently fed in one direction and a strip of gauze is continuously fed in a direction transverse thereto beneath the strip of absorbent material, mechanism for severing absorbent pads from the strip of absorbent material and depositing the same at intervals lengthwise of the strip of gauze comprising a bed plate for supporting the strip of absorbent material and having a pad delivering opening therein between the forward end of the strip of absorbent material and the

strip of gauze, a cutting die mounted in said opening, a reciprocatory cutting punch mounted for movement into and out of said cutting die to sever a pad from the strip of absorbent material and convey the same downwardly through said die in alinement over said strip of gauze, and means mounted within said cutting punch and movable with respect thereto to strip the severed pads from the punch.

10. In a machine for making sanitary napkins wherein the forward end of an intermittently advanced strip of absorbent material is severed therefrom and transferred to a continuously fed strip of gauze, a pad severing and transferring device comprising a bed plate for supporting the strip of absorbent material for intermittent movement in a given direction, means for supporting the strip of gauze below the strip of absorbent material for movement transversely of the direction of movement of the strip of absorbent material, said bed plate having an elongated opening therethrough in alinement with the said strips, a cutting die mounted in the upper end of said opening, a cutting punch mounted for reciprocatory movement into and out of said die to sever an absorbent pad from the forward end of the strip of absorbent material and transfer the same downwardly into said opening, stripper means for releasing the pad from the cutting punch at the lower limit of the movement thereof, and means for retaining the pad in position in the lower end of said opening and for delivering the same to said strip of gauze upon contact therewith of the subsequently severed pad during the next succeeding downward movement of the cutting punch.

AUGUST P. JURGENSEN.
